IDENTIFICATION OF MATERIALS

Benjamin W. Collins, Swarthmore, Pa., assignor
to American Viscose Corporation, Marcus Hook,
Pa., a corporation of Delaware

No Drawing. Application November 25, 1938,
Serial No. 242,282

4 Claims. (Cl. 106—165)

This invention relates to the manufacture of regenerated cellulose yarns and other shapes containing a foreign substance, by means of which they may be readily identified.

It is desirable to be able to identify the origin and method of manufacture of regenerated cellulose yarns and other shapes. This is often not easy to do, however, for the ordinary means of identification are not permanent and do not give positive results.

It is, therefore, an object of this invention to provide a method of positively identifying the origin and method of manufacture of regenerated cellulose yarns and other shapes.

Other objects and advantages of this invention will become apparent from the following description and appended claims.

Methods of identifying rayon yarns and other shapes have been suggested in the United States Patent to Whitehead 1,885,878. However, the class of foreign substances mentioned in the Whitehead patent are not entirely suitable for identification purposes in yarns or other shapes produced by regenerating cellulose from a cellulose solution. Such compounds as nickel and strontium chloride that are disclosed in the patent as being typical examples of identifying substances are readily soluble in water. By the same token they are readily leached out either during the copious aqueous treatment required in the manufacture and finishing of all regenerated cellulose products or during the subsequent processes to which such goods are commonly subjected, such as kier boiling, dyeing, sizing, soft finishing, and also ordinary laundering in the hands of the ultimate consumer.

In contradistinction to this procedure, I have found that as a class, the most valuable identifying substances are those possessing the highest degree of insolubility in water as well as in solutions of acids, alkalies, desulphiding agents, bleaching agents, soaps, oils, or oily emulsions as well as organic solvents such as may be used, for instance, in dry cleaning establishments. Furthermore, I have found that substances possessing such highly desirable characteristics may be successfully introduced into the cellulose solution from which the cellulose product is to be regenerated, in the form of exceedingly finely divided suspensions in which the diameter of the larger particles is of the order of 0.45 micron (0.00045 mm.). In such states of subdivision or colloidal dispersion, the particles readily pass through the interstices of ordinary filtration media as well as through the apertures of the

spinnerets. Furthermore, as a means of providing a permanently and uniformly distributed identifying material the insoluble particles offer the added advantage of remaining firmly fixed in the yarn or shape. They cannot be washed away or moved from their original positions as is true in the case of soluble compounds which exhibit definite tendencies to localize or concentrate in the lower portions of skeins or fabrics hung up to dry.

Having described the advantages of such highly insoluble materials, I now cite several typical examples and will describe in greater detail methods for their successful introduction into the viscose process. I may employ, by way of illustration, insoluble substances comprising compounds of gold, copper, silver, lithium, barium, cadmium, beryllium, lanthanum, boron, tin, thorium, cerium, zirconium, bismuth, arsenic, 15 antimony, tantalum, uranium, chromium, molybdenum, tungsten, cobalt, praseodymium, and neodymium; such as the silicates of these metals, the oxides of beryllium, zirconium, bismuth, tantalum, chromium, molybdenum and tungsten; such organic derivatives as the oleates, 20 stearates and laurates of copper, silver, barium, cadmium, beryllium, tin, zirconium, bismuth, chromium, and cobalt; and various glasses to which these metals or compounds thereof have 25 been added. I may also employ the naturally occurring mineral ores such as spodumene, which is a double silicate of aluminum and lithium; tourmaline, which is usually a combination of lithium, sodium, potassium, iron, magnesium, and 30 manganese silicates; cerite, which contains silicates of cerium and allied materials; gadolinite, which usually contains silicates of iron, beryllium, yttrium, cerium, and erbium; and monazite, which usually contains silicates, phosphates of 35 certain rare elements such as cerium, neodymium, praseodymium, lanthanum, and thorium.

These substances may be used separately or several of them together.

Any sufficiently insoluble compound of any of 45 these or similar metallic bases may be reduced in ordinary pebble mills to the approximate particle size mentioned above. The suspension in proper amounts then may be added at any convenient stage in the viscose process prior to the spinning operation, providing, of course, that the particles 50 are subjected to thorough mechanical mixing to distribute them uniformly throughout the cellulose solution.

I prefer to add the very smallest amount of 55 the substance compatible with positive identi-

fication requirements, which may vary from less than 1 part to 5 parts of the identifying substance per million parts by weight of the finished yarn or shape. Particles of this order of magnitude and in the very small amounts that are used do not change the physical characteristics or perceptible general appearance of the yarns or shapes produced. It is found that it requires about 1200 parts of foreign substance per million parts of the yarn or shape in order to effect 10 a perceptible change in their general appearance.

Obviously the laboratory procedures for effecting the identification of cellulose products produced in this manner will vary according to 15 whichever may be the most sensitive characteristic reaction of the substance in question. The amounts of the substance used may be proportioned to the sensitiveness of the identification procedure, whether it be a delicate color reaction, a characteristic precipitate or the result of a spectrographic analysis.

While I find that the above examples give the most desirable results, I do not wish to be limited to only these, for my invention covers the use of other insoluble compounds as well. Also 20 although the invention has been described in connection with the viscose process, it is to be understood that the invention is applicable to other processes of regenerating cellulose from a cellulose solution and is intended to cover yarns, threads, filaments, staple fibers, films, coatings, and other shapes of regenerated cellulose.

Having thus described my invention, what I claim is:

1. A cellulosic spinning solution for the production of cellulosic shapes containing, in an amount insufficient to change the perceptible general characteristics of the shape, of the order of less than 1200 parts per million parts of the shape, a material by which the shape may be identified comprising an oxide of a member selected from the group consisting of beryllium, zirconium, bismuth, tantalum, chromium, molybdenum and tungsten.
2. A cellulosic spinning solution for the production of cellulosic shapes containing, in an amount insufficient to change the perceptible general characteristics of the shape, of the order of less than 1200 parts per million parts of the shape, a material by which the shape may be identified comprising beryllium oxide.
3. A cellulosic spinning solution for the production of cellulosic shapes containing, in an amount insufficient to change the perceptible general characteristics of the shape, of the order of less than 1200 parts per million parts of the shape, a material by which the shape may be identified comprising zirconium oxide.
4. A cellulosic spinning solution for the production of cellulosic shapes containing, in an amount insufficient to change the perceptible general characteristics of the shape, of the order of less than 1200 parts per million parts of the shape, a material by which the shape may be identified comprising molybdenum oxide.

BENJAMIN W. COLLINS.
